COMBINED COLD BEVERAGE AND FROZEN FOOD MERCHANTISER

Eugene Buday, Wilkins Township, Allegheny County, Pa.
(324 Sunset Drive, Pittsburgh, Pa. 15235), and Sol
Blackman, 1152 Towanda Terrace, Cincinnati, Ohio
45216

Filed Dec. 6, 1974, Ser. No. 530,442

Term of patent 7 years

Int. Cl. D20—02

U.S. Cl. D6—187

FIG. 1

FIG. 2

FIG. 3

FIG. 6

FIG. 5

FIG. 4

FIG. 1 is an enlarged perspective view of a combined cold beverage and frozen food merchandiser showing our new design;

FIG. 2 is a top plan view thereof;

FIG. 3 is a bottom plan view thereof;

FIG. 4 is a front elevational view thereof;

FIG. 5 is a side elevational view thereof, the opposite side being identical;

FIG. 6 is a rear elevational view thereof.

We claim:

The ornamental design for a combined cold beverage and frozen food merchandiser, as shown and described.
